CLYDE H. BOLMSEEE, OF CRANFORD, NEW JERSEY, ASSIGNOR TO AMERICAN CAR AND FOUNDRY COMPANY, OF NEW YORK, N. Y., A CORPORATION OF NEW JERSEY.

TANK-CAR DISCHARGE.

Application filed May 6, 1927. Serial No. 189,322.

Reference is had to the accompanying drawings which illustrate the preferred form of the invention, though it is to be understood that the invention is not limited to the exact details of construction shown and described, as it is obvious that various modifications thereof within the scope of the claims will occur to persons skilled in the art.

10 In said drawings:

Figure 1 is a section through a car tank showing the valve and its associated parts in section;

Fig. 2 is a vertical sectional view of the 15 valve;

Fig. 3 is a sectional view on the line 3—3 of Fig. 2;

Fig. 4 is a sectional view on the line 4—4 of Fig. 2;

20 Fig. 5 is a sectional view on the line 5—5 of Fig. 2, and

Fig. 6 is a sectional view on the line 6—6 of Fig. 2.

This invention relates to an improved car 25 tank discharge means, and more particularly, comprehends a discharge valve and a valve stem adapted to receive heat from a heat discharge outlet.

It is an object of the present invention to 30 provide a valve, a valve stem or rod and a valve operating means for a car tank or the like, which parts are heated whereby to maintain the lading of the tank car in such fluidity that the same may be readily discharged through the outlet.

Another object of the invention is to provide a novel construction of discharge valve and valve operating means for tanks or the like.

Referring now more particularly to the drawings, A indicates a car tank having a bottom 1 and a top 2, the latter being provided with a dome 3. The bottom is provided with a discharge outlet comprising a jacketed casting 4 having an inlet pipe 5 and an outlet pipe 6 and a central discharge opening 7. The casting is interiorly threaded adjacent the tank end as shown at 8 and has mounted therein an externally threaded annular ring 9 which screws into the tank end of the casting and is formed with a valve seat 10 upon which the lower end of a valve B is adapted to seat.

The ring 9 is provided with vanes 10'

which extend upwardly therefrom and are 55 preferably formed integral with a tubular carrier element 11 in the form of a sleeve, the latter having an external thread 12. The construction just described forms a valve guide and carrier as will be hereafter described.

The valve B comprises a sleeve 13 having its lower edge 14 formed to engage the valve seat 10, and its upper end is reduced as shown at 15 and internally threaded to engage the lower end of a tubular valve rod 16. Locking means such as shown at 17 are provided, the same having screws 18 engaged in grooves defined by adjacent ribs 19 for rotating said valve with the rod 16. The 70 upper end of the valve rod extends into the dome 3 and is carried in a bracket 20, and the extreme end of the rod 16 is provided with a coupling 21 supporting an operating means 22 such as a hand wheel or the like, 75 and said coupling also mounts a nipple 23 having a vented splash cup 24 at the end thereof.

The valve B is provided with spaced internal shoulders 25 and 26 respectively as 80 clearly indicated in Fig. 2, which shoulders serve as limiting stops for an actuator 27 in the form of a sleeve nut, the same being internally threaded to engage and work on the threads 12 of the carrier element or sleeve 11, 85 said nut being provided with spaced lugs 28 adjacent the lower edge thereof.

The shoulders 26 are provided with recesses which recesses aline to form substantially a circumferential groove for supporting a spring ring 29 which, as clearly shown in Fig. 1, supports a vertically arranged plate 30 positioned between adjacent shoulders 26 and serving as an abutment or operating member as hereafter described. 90 Referring to Fig. 1, it can be seen that the abutment 30 extends upwardly beyond the horizontal plane of the shoulders 25, and the valve B has its casing so formed, as shown at 31, as to provide a recess in the side thereof to accommodate the upper end of said abutment 30 and to prevent lateral movement thereof with respect to the valve.

With a valve construction as described, the operating mechanism therefor is located 105 within the sleeve or shell 13 and hence shielded from direct contact with the tank lading.

Assuming the parts to be in the position illustrated in Fig. 1, that is, with the edge 14 of the valve B in engagement with its seat 10, it is seen that the lug 28 is seated on the shoulder 26. To open the valve, the hand wheel 22 is rotated thus turning the sleeve 13 and the abutment 30, the latter contacting with one of the lugs 28, thereby turning the sleeve nut 27 on the carrier 11 and elevating said nut. Continued rotation of the valve will bring the lugs 28 into contact with the upper shoulder 25, and during the rotation of the sleeve nut 27 on the carrier 11, and up to the time of the engagement of the lugs 28 with the shoulder 25, the valve B still remains on the seat 10 rotating thereon and during such rotation, it will be apparent that the edge of the valve B is ground to its seat 10. The continued rotation of the sleeve 27 as before mentioned will bring the lugs 28 into contact with the shoulder 25 and cause the valve B to be raised from its seat by said lugs, thereby opening the discharge outlet to permit the discharge of the contents of the tank. A reversal of rotation of the valve rod 16 will cause the nut 27 to be lowered, thus engaging the lower shoulder 26 and forcing the valve B to seating position, and when the valve B reaches seating position, continued rotation thereof will also serve to grind the edge of the valve on the seat 10 and also lower the sleeve 27 until it reaches the position shown in Fig. 1 with the lugs 28 in contact with the lower shoulder 26 at which time the valve B is positively retained on its seat 10 by the engagement of the lugs 28 with the shoulder 26, as will be obvious.

It is to be noted that with the construction just described, there is provided a continuous opening through the valve, valve rod and cap 24 to the dome. As before-mentioned, the discharge outlet is jacketed permitting a heating medium, such as steam, to be passed from the inlet 5 through the jacket and out through the outlet 6, thereby heating said casting or discharge outlet, and because of such heating, the air in the discharge outlet passage 7 will be heated and will be passed upwardly, past the vanes 10' and through the hollow carrier 11 into the valve B and then upwardly through the valve rod 16 and into and out of cap 24, this passage of heat serving to heat the contents of the tank adjacent the valve and its rod, thus aiding in maintaining the fluidity of such contents.

The casting 4 is provided with tapped openings which are, in the instance shown, closed by plugs 31'. These openings are provided for the purpose of permitting the attachment of heating coils for the interior of the tank to the casting whereby to circulate a heating medium throughout the contents in the tank. This construction

being well known in the prior art is not specifically shown nor is any claim made thereto.

What is claimed is:

1. In a tank, a jacketed discharge nozzle therefor receiving steam for heating the same, a hollow valve closing said discharge nozzle and a hollow valve rod for operating said valve, said valve and valve rod receiving heat from said nozzle whereby to heat the lading in the tank.

2. In a tank, a discharge nozzle having a valve seat, a valve for controlling discharge through the nozzle, a carrying element supported by the valve seat, a valve operating sleeve mounted on said carrying element, and means on said valve adapted to engage said sleeve to rotate the latter upon rotation of the valve whereby said valve is raised or lowered.

3. In a tank car discharge valve, a valve seat member, a valve member rotatable on said seat member to grind said valve member, a carrying element supported by said seat member, and a sleeve member around said carrying element and adapted to contact with said valve member to raise the same from the seat member during rotation of the valve member and after the commencement of rotation.

4. In a tank, a discharge nozzle having a valve seat, a valve for controlling the discharge through said nozzle, a valve rod fixedly secured to the valve, a carrying element supported by the valve seat, and means interposed between the valve and carrying element and longitudinally movable on the outer surface of the latter for engaging the valve after partial rotation thereof to raise said valve.

5. In a tank, a jacketed discharge nozzle receiving a heating medium, a hollow valve normally closing said nozzle, a hollow valve rod for operating the valve, said valve and valve rod receiving heat from the nozzle to heat the tank lading, and means in the valve for operating the latter upon rotation of said valve.

6. In a tank, a jacketed discharge nozzle receiving a heating medium, a hollow valve, a hollow valve rod secured to the valve, a hollow carrying element connected to the nozzle, said valve carrying element and valve rod receiving heat from the nozzle to heat the tank lading, and means interposed between the valve and carrying element and engaging the latter to operate said valve upon rotation of the latter.

7. In a tank, a jacketed discharge nozzle receiving a heating medium, a hollow valve, a hollow valve rod secured to the valve, a hollow carrying element connected to the nozzle, said valve carrying element and valve rod receiving heat from the nozzle to heat the tank lading, and means interposed be-

tween the valve and carrying element and engaging the latter to elevate said valve after partial rotation of the latter.

8. In a tank having a valve and a valve rod, means for operating said valve comprising a fixed carrying element, means interposed between the valve and carrying element and working on the latter, and an abutment rotatable with the valve for operating the beforementioned interposed means on the carrying element.

9. In a tank having a jacketed discharge nozzle receiving a heating medium, a hollow valve and valve rod receiving heat from the nozzle to heat the tank lading, and valve operating mechanism in said valve.

10. In a tank having a jacketed discharge nozzle receiving a heating medium, a hollow valve and valve rod receiving heat from the nozzle to heat the tank lading and valve operating mechanism in said valve operable to raise said valve only after partial rotation of the latter.

11. In a tank, a discharge nozzle having a valve seat, a valve, a valve rod connected to the valve, a carrying element supported by the valve seat and arranged within the valve, and means rotatable on the outer surface of the carrying element for permitting rotation of the valve on its seat and for engaging said valve after rotation thereof on its seat whereby to elevate said valve.

12. In a car tank discharge valve, a rotat-

able valve member, a fixed carrying element arranged within the valve member, and a sleeve member surrounding said carrying element and movable longitudinally thereon, said sleeve member being so arranged as to contact with the valve member to elevate the same after partial rotation of said sleeve member and said valve.

13. In a car tank discharge valve, a rotatable valve member, a fixed carrying element arranged within the valve member, and a sleeve member surrounding said carrying element and movable longitudinally thereon, said sleeve member being so arranged as to contact with the valve member to elevate the same only after partial rotation of said valve.

14. In a tank, a discharge nozzle having a valve seat, a valve for controlling the discharge through the nozzle, a valve rod arranged within the tank, a carrying element supported by the valve seat and arranged within the tank, an actuator longitudinally movable on the outer surface of the carrying element by the valve, and means formed on the actuator for engaging the valve to elevate the latter after partial rotation of said valve and for forcing said valve to its seat when the valve is lowered.

In witness whereof I have hereunto set my hand.

CLYDE H. FOLMSBEE.
